Attorney

UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

TYPEWRITING MACHINE.

Application filed February 1, 1922. Serial No. 533,222.

To all whom it may concern:

Be it known that I, WILLIAM F. HELMOND, a citizen of the United States, residing in Hartford, in the county of Hartford and 5 State of Connecticut, have invented certain new and useful Improvements in Type-writing Machines, of which the following is a specification.

This invention relates to type actions for 10 typewriting machines, and a feature of the invention is to control the character of the type impressions and to reduce the noise caused by the type-bars striking the platen.

In carrying out the invention, a stop is 15 employed to arrest the key-levers before the type-bars strike the platen, and lost motion is provided in the connection between each key and the type-bar to allow the type-bar to continue in its movement, independently of the keys, by momentum, and print. 20 With this lost-motion connection, the type-bars strike the platen with less force than would result if they could be followed up all the way to the platen by the pressure on the 25 key-levers.

Thus the inked type impressions on the paper may be lightened and sharpened and noise of the type blows may be reduced.

The stop for the key-levers may be adjustable 30 to vary the distance of the independent movement of the type-bars. This distance may be decreased to cause the type-bars to strike with a greater force against the platen when manifolding. When it is desired to 35 make a very large number of manifold copies, the stop may be thrown entirely out of action.

Another feature of the invention is to 40 increase the promptness of the return stroke of the escapement mechanism, so as to increase speed of operation and evenness of letter-spacing. This is brought about by the partial independent return movement of the type-bar at the initial part of its return stroke, while the finger of the operator is 45 momentarily holding the key at the bottom of its stroke.

The stop may be regulated to a point to

secure the clearest impressions of the type upon the work-sheet. Moreover, by varying the position of the stop, the depth of color of the inked impressions on the sheet may be varied at will, which is a desideratum in typing in the addresses on mimeographed and multigraphed circulars, where 55 it is desired that both the address and the body of the circular be typewritten.

Other features and advantages will hereinafter appear.

In the accompanying drawings, 60 Figure 1 is a side view of an Underwood type action and part of the carriage-escapement mechanism, illustrating the invention in connection therewith, and showing the parts in normal positions.

Figure 2 shows the type-bar moved by the key-lever to the position from which it travels independently to the platen.

Figure 3 shows the type-bar operated and the key-lever stop rendered ineffective.

Figure 4 is a fragmentary sectional front view, showing how the key-lever stop is supported in the machine frame.

Key-levers 10 when depressed swing about fulcrums 11 against the tension of return springs 12 to rock bell-crank 13 about their pivots 14 and swing type-bars 16 upwardly and rearwardly to print against the front side of a platen 17. The type-bars are pivotally supported on a curved rod 18 in a type-bar segment 19, and are guided in radially-disposed slots 20 to a common printing point and strike the usual type-bar arrester 21 on the segment. Each type-bar is provided with a heel 22 to engage a universal bar 23^a to push a universal frame 23 rearwardly, and, by means of a cross-bar 24 on said universal frame, swing the upper end of a dog-rocker 25 rearwardly to disengage a loose dog 26 from the usual escapement wheel 27 and move a fixed dog 28 into the path of said wheel, said escapement wheel having the usual connection with a carriage, not shown, which supports the platen 17. The usual return springs, not shown, may be employed to restore the dog-

rocker and the universal frame to normal positions, the feeding of the carriage being effected upon the return stroke of the dog-rocker, or, in other words, when the loose dog 26 re-engages the escapement wheel.

The key-levers 10 are arrested by a stop 29, engaged by shoulders 30, before the type-bars reach the platen. Lost motion is provided in the connection between each key-lever 10 and each bell-crank 13, there being a stud 31 on each key-lever to engage between two prongs 32 and 33 formed by a slot 33^a in each bell-crank 13, and each slot being wider than the diameter of the stud, thus producing the lost motion. Consequently, the key-lever moves idly for a slight distance from the Figure 1 position until the stud reaches the lower prong 32 of the bell-crank. The key-lever then drives the type-bar to the Figure 2 position, where the key-lever engages the stop 29 and is consequently arrested. It will be seen that in this position the upper prong of the bell-crank is out of engagement with the stud on the key-lever, and consequently the type-bar is free to continue in its movement, under the influence of its attained momentum, to strike against the platen. By arresting the key-lever, the force is somewhat broken, and consequently the type-bar prints against the platen with less noise. Since the distance of travel of the key-lever in the location of the stop 29 is very slight, any sound which might be produced by the contact of the key-lever with said stop is practically negligible. Upon the return stroke of the key-lever, the stud engages the upper prong 33 of the bell-crank to rock the latter and swing the type-bar back to its normal position.

The form of stop 29 herein shown is cylindrical and is pivotally and eccentrically supported by trunnions 34 at its ends pivoted in the machine frame 35, so that the stop may be adjusted to vary the distance between it and the engaging shoulders 30 of the key-levers to change the force with which the type-bars strike the platen when making a greater or smaller number of manifold copies. The stop 29 may be rendered entirely ineffective by rotating it to the position shown in Figure 3, when it is desired to type through an extremely thick pack of manifold sheets.

To manipulate the key-lever stop, there is provided at its right-hand end a finger-wheel 36 which may be secured to the trunnion 34. Said stop may be held in its various positions of adjustment by means of a spring detent 37 engaging in notches 38 of a sector 39 secured to the trunnion 34, said sector being herein provided with four notches settable to four positions and engaging with two stops 40 and 41 to limit the rotary movement of the key-lever stop in its two ex-

treme positions, thus preventing accidental disengagement of the detent spring with the sector.

It will be understood that with this arrangement the speed with which the carriage feed is effected is greatly increased, due to the fact that the type-bar, on account of the lost-motion connection with the key-lever, may start on its return movement before the key-lever, and may move as far back as the position shown in Figure 2, which is sufficient to allow the return of the universal bar and consequently of the escapement devices, thus affording an early start in the letter-spacing movement of the carriage, and avoiding any undue delay which may otherwise be caused by the key-lever.

Variations may be resorted to within the scope of the invention, and portions of the improvements may be used without others.

Having thus described my invention, I claim:

1. In a typewriting machine, the combination of a platen, key-levers, type-bars, bell-cranks connecting the key-levers with said type-bars, a revoluble stop disposed beneath the key-levers to arrest them, each bell-crank having a lost-motion connection with its key-lever to allow the type-bar to travel by its attained momentum to print against the platen after the key-lever has been arrested, and means to adjust said stop about its axis to vary the distance the type-bar may travel after the key-lever has been arrested.

2. In a typewriting machine, the combination of a platen, type-bars, key-levers, bell-cranks connecting said type-bars with said key-levers, the bell-cranks having slots, studs on the key-levers to engage in the slots, the width of the slot of each bell-crank being slightly greater than the diameter of the stud of the associated key-lever to afford a lost-motion connection between the bell-crank and the key-lever, and a stop to arrest the key-lever before the type-bar strikes the platen, the lost motion being provided so that the type-bar by its attained momentum is caused to continue in its movement and print against the platen after the key-lever has been arrested.

3. In a typewriting machine, a carriage, a platen therein, type-bars carrying types to print against the platen, key-levers to actuate the type-bars, means operatively connecting the key-levers and type-bars, comprising loose pin-and-yoke connections, and means to arrest each key-lever on the printing stroke of its type-bar, the loose pin-and-yoke connection being effective to permit the type-bar to travel by its attained momentum to print against the platen after its key-lever has been arrested, and to cause the type-bar to pick up the key-lever on its return stroke and return to normal position

concurrently with the key-lever and in operative relation to it.

4. The combination with a platen, of a set of type-bars, operating keys, individual connections between the keys and the type-bars, means common to the keys to engage and arrest certain portions of said connections as the types approach the platen, to permit

the types to complete their printing strokes by momentum, by reason of looseness in the 10 connections between said arresting means and the type-bars, and means for moving said arresting means to ineffective position and to different working positions, to vary the type blows.

WILLIAM F. HELMOND.
